(57) **CLAIM**

The ornamental design for a base for handheld nail treatment device, as shown and described.

DESCRIPTION

FIG. 1 is a top plan view of the base for handheld device shown in an operational environment including a stand and the handheld device;

FIG. 2 is a first perspective view of the base for handheld nail treatment device shown in FIG. 1;

FIG. 3 is a second perspective view of the base for handheld nail treatment device shown in FIGS. 1 and 2;

FIG. 4 is top plan view of the handheld device shown in FIGS. 1 and 2;

FIG. 5 is bottom plan view of the base for handheld nail treatment device shown in FIGS. 1 and 2;

FIG. 6 is a front side elevation view of the base for handheld nail treatment device shown in FIGS. 1 and 2;

FIG. 7 is a rear elevation view of the base for handheld nail treatment device shown in FIGS. 1 and 2;

FIG. 8 is a first side elevation view of the base for handheld nail treatment device shown in FIGS. 1 and 2; and,

FIG. 9 is a second side elevation view of the base for handheld nail treatment device shown in FIGS. 1 and 2.

The elements illustrated in FIG. 1 by broken lines form no part of the present invention.
